(57) **CLAIM**

The ornamental design for an automobile wing, substantially as shown and described.

DESCRIPTION

FIG. 1 is a rear left perspective view of an automobile wing, showing my new design;

FIG. 2 is a left side view thereof, it being understood that the right side is a mirror image thereof;

FIG. 3 is a front view thereof;

FIG. 4 is a rear view thereof;

FIG. 5 is a top view thereof; and,

FIG. 6 is a bottom view thereof.

The broken lines in FIGS. 1, 4 and 5 depict a tail light.
